UNITED STATES PATENT OFFICE.

AUGUST HARDING, OF OAKLAND, CALIFORNIA.

INCANDESCENT ELECTRIC LAMP.

SPECIFICATION forming part of Letters Patent No. 333,219, dated December 29, 1885.

Application filed March 20, 1885. Serial No. 159,598. (No model.)

To all whom it may concern:

Be it known that I, AUGUST HARDING, of 5 Oakland, Alameda county, State of California, have invented an Improvement in Incandescent Electric Lamps; and I hereby declare the following to be a full, clear, and exact description of the same.

My invention relates to that class of electric lamps in which a continuous carbon-conductor 10 is heated in a vacuum to incandescence.

My invention consists in a peculiar air-tight joint between the globe and base of the lamp, all of which will be hereinafter described and claimed.

15 Figure 1 is a vertical section of my lamp, showing the globe mounted on its base. Fig. 2 is a cross-section on line X X, Fig. 1, showing the pawl and ratchet. Fig. 3 is a vertical section of the lamp as modified to avoid fusing 20 the in-leading wires in the glass.

In lamps of this description it is usually the case that when the carbon conductor is destroyed by use or accident the lamp is worthless. Then, again, in order to exhaust the lamp, 25 glass tubes in some cases are attached to the globe, and, finally, a perfect vacuum is not obtained by reason of the failure to expel all the occluded gases.

The object of my invention is to overcome 30 these several difficulties by constructing a lamp the globe of which can be readily separated from the base and the carbon conductor replaced without injury to any of the parts 35 of the lamp; and, further, by so making the lamp as to adapt it to become subject to the peculiar means employed to expel the occluded gases and to fit its parts together within an exhausted chamber, whereby it is itself thoroughly exhausted.

40 A is the glass globe, having a neck, a.

B is a tube of soft metal, such as sheet-lead, having flanges b at top and bottom, and a central flange, b', though this latter flange is not essential, and may be omitted, if desired.

45 C is a tube of hard metal encircling tube B and its flanges, whereby an annular chamber, c, is formed between its inner wall and the outer wall of tube B. The tube C has a diaphragm, c', which forms between itself and the bottom of the tube a chamber, c''. Into this chamber extends downwardly a stud, c'',

in which a canal or passage, D, is made, which extends through the diaphragm c' and connects with the chamber c, as shown.

55

Upon the stud c'' is fitted a sleeve, E, forming a bearing or seat for a valve, e, which is adapted to close or open the mouth of the canal D. This sleeve has a port, e'. The valve is on the upper end of a screw-stem, e', 60 threaded in the sleeve, and having keyed upon its lower end a ratchet-wheel, e'', which is controlled by a pawl, e'', made of soft iron. Through the base of chamber c'' is formed a passage, c', in which a plug, c'', is adapted to 65 fit.

Secured by one end to the ratchet-wheel e'' is a coil-spring, F, the other end of which is secured to the sleeve E. This spring is so arranged as to have a tendency to turn the 70 ratchet in a direction to unscrew the stem e', and thus remove the valve e from the canal. A square hole is made in the bottom of the ratchet-wheel, as shown in Fig. 2, for the 75 reception of a key projected through passage c', whereby the ratchet may be rotated to screw the valve upward to its seat and close the canal. This movement of the ratchet winds up the spring, and said ratchet is held by the pawl e''. When the pawl is released, the 80 spring rotates the ratchet to remove the valve and open the canal.

G is a glass plug fitted within the soft-metal tube B, its base resting on the diaphragm c'. It extends upwardly about half-way of the 85 tube B, and then is reduced in diameter, forming shoulders g, from which point it extends upwardly in the form of a spur, g', having an ear, g''.

Upon the shoulders g rests a metallic ring, H, lying closely within the metal tube B. The neck a of the globe fits down closely within the upper portion of the soft-metal tube, its base resting on the metal ring H.

Around the lower portion of the external 95 tube C is a metal ring or band, I, which is insulated therefrom by the use of a proper lining.

J J' are the in-leading wires. The wire J forms a contact with the ring H, and thence extends upwardly through the neck of the globe and through the ear g', ending in a spiral, j, having a projecting end, Fig. 6. The wire J' forms an external contact with the insulated

ring I, and thence passes into the lamp through the glass plug G, up through its spur g', and terminates in a similar spiral, j, having a projecting end.

5 X is a carbon conductor within globe A. Its ends are passed into the spiral j of the wires, and are there secured by means of a carbon-paste.

The object of the construction thus far explained is as follows: For the purpose of mounting the glass globe A on the base, the annular chamber c, the canal D, and part of the chamber c² are filled with any suitable liquid or gas—such, for example, as glycerine or carbonic acid—the chamber c² being filled to such a point that the mouth of the canal D is under the surface of the liquid in any position of the lamp. The valve e is then screwed up to its seat, as heretofore explained, thus closing the canal. The rest of the chamber c² is now filled with a compressed gas and the plug c⁵ is replaced while under pressure.

To complete this description for the better understanding of the device, I will anticipate subsequent steps by supposing the entire lamp to be exhausted. The globe is placed within the soft-metal tube B, as heretofore explained. A strong magnet is then brought to act from without upon the pawl c³, which is thus caused to release the ratchet, which, under the influence of its spring, opens the valve e, whereupon the liquid in chamber c is brought under high pressure, forcing the soft metal of tube B around the glass parts of the lamp, making an air tight joint between them. To complete this joint it will be found necessary to previously apply a cement—such as gutta-percha or Canada balsam—between the soft metal and the glass. To remove the globe, 40 the plug c⁵ is taken out, thus relieving the joint of pressure.

In Fig. 3 I show a modified form of the lamp which may be used if it be found desirable to avoid the fusing of the metallic wires into the glass. In this case two separate metallic parts or joints are used, constructed as heretofore described. The upper one is permanently attached to the neck of the globe and to a glass tube, K, which projects down into and is connected in the manner described to the lower one. A metallic ring, k, lies in contact with the soft-metal tube of the upper joint, and carries a contact-spring, k', which makes electrical connection with the ring k and the inner leading wire J'. The wire J' is insulated from the lower joint at j', while the wire J is electrically connected with said joint, as shown. The glass tube K may be removed from the lower joint when the pressure in the chamber c is relieved, as heretofore described.

Having thus described my invention, what I claim as new, and desire to secure by Letters Patent, is—

1. In an incandescent electric lamp having 65 a glass globe containing the carbon conductor, and a metallic base, the means for joining the globe to the base, consisting of an air-tight

compression-chamber encircling the neck of the globe and binding it to the base, substantially as herein described.

70

2. In an incandescent electric lamp having a glass globe and a metallic base, the means for joining the globe and base, consisting of an annular chamber encircling the neck of the globe, and having its inner wall of soft metal adapted under pressure to be forced against the glass, substantially as herein described.

75

3. In an incandescent electric lamp, the annular chamber c, encircling the neck of the glass globe, and having its inner wall of soft metal, and a connection between said chamber and a chamber containing liquid or gas under pressure, whereby a pressure is brought upon the soft-metal wall to force it around the glass, substantially as herein described.

85

4. In an incandescent electric lamp, an air-tight joint between the globe and base of the lamp, made by compressing a tube of soft metal around the neck of the globe, the impinging-surface being provided with cement, and keeping the tube under pressure while ready for use, substantially as herein described.

90

5. In an incandescent electric lamp, the soft-metal tube B, having flanges, and the exterior hard-metal tube, C, encircling the tube B, whereby an annular chamber, c, is formed, substantially as and for the purpose herein described.

95

6. In an incandescent electric lamp, the soft-metal tube B, having flanges, and the exterior hard-metal tube, C, encircling tube B, forming an annular chamber, c, in combination with the glass globe A, having neck a, fitted within the soft-metal tube, the impinging-surfaces being provided with cement, and a means for admitting pressure to the chamber c, whereby the soft-metal tube is forced tightly around the neck a, substantially as herein described.

105

7. In an incandescent electric lamp, the soft-metal tube B, having flanges b, the hard-metal tube C, encircling tube B and forming a chamber, c, in combination with the glass globe A, having a neck fitting within the soft-metal tube, the impinging-surfaces being covered with cement, the chamber c² below, and the canal D, connecting the two chambers, substantially as herein described.

110

8. In an incandescent electric lamp, a soft-metal tube and an encircling hard-metal tube, forming between them an annular chamber, a chamber formed in the base of the hard-metal tube, containing liquid or gas under pressure, a canal connecting said chamber with the annular chamber, and a valve for closing the mouth of the canal, in combination with the glass globe, the neck of which is fitted within the soft-metal tube, substantially as and for the purpose herein described.

120

9. In an incandescent electric lamp, an annular chamber encircling the neck of the glass globe and having its inner wall of soft metal, in combination with a chamber containing a liquid or fluid under pressure and connected with the annular chamber, a spring-valve con-

125

130

trolling the connection and held to its seat by a metallic pawl adapted under the influence of a magnet to relieve the valve and establish the connection between the two chambers, 5 whereby the soft-metal wall is pressed around the glass neck, substantially as herein described.

10. In an incandescent electric lamp, the soft-metal tube B and the hard-metal tube C, forming an annular chamber, c, the chamber c² in the base of the hard-metal tube, the canal D, connecting chambers c² e, the valve e, controlling the canal, the screw-stem e' of the valve, the ratchet e² on the stem, the operating-spring F, and the retaining-pawl e³, all arranged and adapted to operate substantially as and for the purpose herein described.

11. In an incandescent electric lamp, the globe A, having neck a, and the underlying glass plug G, in combination with the soft-metal tube B, encircling the neck and glass plug, the hard-metal tube C, encircling the tube B and forming an annular chamber, c, the compression-chamber c², connecting-canal D, and controlling-valve e, all arranged and adapted to operate substantially as herein described.

12. In an incandescent electric lamp, the globe A, having neck a, and the glass plug G, 30 in combination with the encircling soft metal

tube B, the exterior hard-metal tube, C, forming chamber c, the chamber c² in the base of the tube C, the canal D, connecting the two chambers, the screw-valve e, controlling the canal, the ratchet e², spring F, and pawl e³, by 35 which the valve is operated and held, the entrance-passage c⁴ to the chamber c², and the plug c⁵, all arranged and adapted to operate substantially as herein described.

13. In an incandescent electric lamp, the 40 combination of the globe A, having neck a, the glass plug G, having spur g', the metallic ring H between the neck of the globe and the glass plug, the encircling concentric tubes B C, the former of soft metal, and having a chamber, c, between them, the chamber c² below, having an entrance, c⁴, the canal D, connecting the chambers, the valve e, controlling the canal, the ratchet e², pawl e³, and spring F, exterior insulated metallic ring, I, and the 45 leading wires J J', connecting the carbon conductor with the metallic rings H I, all substantially as and for the purpose herein described.

In witness whereof I have hereunto set my 55 hand.

AUGUST HARDING.
